UNITED STATES PATENT OFFICE.

AUGUSTUS E. LYON, OF SALT LAKE CITY, UTAH.

DESIGN FOR A BADGE.

SPECIFICATION forming part of Design No. 35,973, dated July 8, 1902.

Application filed May 16, 1902. Serial No. 107,692. Term of patent 7 years.

To all whom it may concern:

Be it known that I, AUGUSTUS E. LYON, a citizen of the United States, residing at Salt Lake City, in the county of Salt Lake and State of Utah, have invented and produced a new and original ornamental Design for a Badge; and I do hereby declare the following to be a full, clear, and exact description of the same, reference being had to the accompanying drawing, forming a part thereof.

My invention relates to a new and original ornamental design for a badge; and its object is to provide a useful and ornamental one having symbols and letters indicative of a society known as the "Elks."

My new design is illustrated in the accompanying drawing by a view in front elevation.

Referring to the drawing, 1 designates a central plate, having a radially-corrugated star-shaped rim 2 and a central radially-corrugated portion 2^a, to which is attached an elk-head 3. A circumferential border formed of twelve elk-teeth surround the plate 1, the points of

the teeth lying beneath the star-shaped rim and having the figure of a clock marked thereon to represent a dial. The outer edges of the teeth are curved to form a scalloped circumference, and their contiguous edges are covered with twisted wire 5. Secured to the central elk-head 3 by means of a pin 7 are the hands 6, arranged to denote the hour of eleven. Four elk-heads 8 project diametrically from the periphery of the badge. The letters "G" and "R" are suspended from the elk-heads on the sides by means of a chain 10, and the letter "E" is similarly suspended from the elk-head at the bottom.

What I claim is—

The ornamental design for a badge, substantially as shown and described. 40

In testimony whereof I affix my signature in presence of two witnesses.

AUGUSTUS E. LYON.
